CLAIM

The ornamental design for a cage for cooking poultry as
shown and described.

DESCRIPTION

FIG. 1 is a perspective view of a cage for cooking poultry showing our new design;

FIG. 2 is a top plan view thereof, with the handles in
the closed position;

FIG. 3 is a bottom plan view thereof;

FIG. 4 is a right side elevational view thereof, the left

side elevational view being a mirror image thereof; and,

FIG. 5 is a front elevational view thereof, the rear eleva-

tional view being a mirror image thereof.
